UNITED STATES PATENT OFFICE.

EDWARD J. VON PEIN, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed July 28, 1924. Serial No. 728,691.

This invention relates to cash registers and is shown carried out in connection with a machine of the type shown in the E. J. Von Pein application, Serial No. 460,882, filed April 13, 1921.

An object of this invention is to provide controlling means which compels the issuing of two receipts for every registration.

With this and incidental objects in view, the invention consists of certain novel features of construction and combinations of parts, the essential elements of which are set forth in appended claims and a preferred form of embodiment of which is hereinafter described with reference to the drawings which accompany and form part of this specification.

Of said drawings:

Fig. 1 is a transverse sectional view taken to the left of the right side frame with parts omitted for clearness.

Fig. 2 is a side elevation of the printer.

Fig. 3 is a transverse sectional view taken to the left of the printer frame.

Fig. 4 is an enlarged detail view of a part of the register controlling mechanism.

Fig. 5 is an enlarged detail view of a part of the controlling mechanism.

Fig. 6 is an enlarged detail view of the parts shown in Fig. 5 but in different relative positions.

Fig. 7 represents a strip of two tickets as printed by the machine.

Fig. 8 is a detail view of a modified form of control mechanism with the parts in home position.

Fig. 9 is a detail view of the mechanism shown in Fig. 8, with certain parts in operated position.

Fig. 10 is a detail view of a portion of the mechanism shown in Fig. 8, with the parts in operated position.

The invention is carried out in connection with a machine of the general type shown in Letters Patents of the United States to Carnegie, No. 497,860 and No. 683,877, granted May 23, 1893 and October 1, 1901, respectively, and is an improvement applied to the machine shown in the E. J. Von Pein application, Serial No. 460,882, filed April 13, 1921.

Described in general terms, the machine comprises a series of manipulative devices

such as item keys which actuate mechanism for indicating items, operate a totalizer, and set up type, and release means for printing on a record strip retained in the machine and on two issuing receipts, the amount entered at each operation of the item keys.

Keys 30 (Fig. 1) pivoted on a transverse rod 31, when depressed, engage and rock a key coupler 32 a sufficient distance to enable an arm 33 pivoted on a stud 34, to swing forward and under the rear edge 35 of the key coupler, in which position the key coupler is retained until after the printing operation has been completed. The key coupler is provided with trunnions 36 having bearings in side frames 37 and 44. Attached to the rear end of each key is an upright member 38 formed with a shoulder 39 adapted, when the key 30 is operated, to engage a transverse rod 40 of a rocking frame 41 pivoted on a transverse rod 42, to rock said frame a distance corresponding to the value of the operated key. There is a frame 41 for each denominational group of keys 30. Each frame has attached to it a registering segment 43.

A main driving shaft 50 is given a revolution in a counter-clockwise direction each time a key is operated. A stud 51 projecting from the right end of the key coupler 32 carries a roller 52 which operates within an opening 53 in a rack plate 54 provided with two groups of rack teeth 55 which alternately mesh with a gear 56 fast to the shaft 50. As the plate 54 is moved upward by depressing a key, the rack 55, which is normally in engagement with the gear 56, will cause the shaft 50 to revolve 180° in a counter-clockwise direction. An ear 57 formed on the plate cooperates with a lug 58 projecting from the side frame to retain said rack in engagement with the gear 56.

Near the end of the upward travel of the plate 54 its end 59 engages an angle face 60 of a spring-drawn arm 61, thereby putting this spring under tension. When the ear 57 passes above the lug 58 the spring arm will cause the plate 54 to swing to the right, thereby disengaging the rack, normally in mesh with the gear 56, from said gear and moving the opposite rack into mesh therewith, and, as the key coupler 32 returns to its normal position, the plate will travel

downward with the ear 57 to the right of the lug 58. As the ear passes beneath the lug 58, a spring 62, attached to the lower end of the plate 54, will return the plate to its normal position, as shown in Fig. 1. The downward travel of the plate 54 completes the cycle of the shaft 50.

The totalizer and indicators, which are of the usual form, are not shown here but are 10 fully illustrated and described in the patents and application previously referred to.

Printer.

Only so much of the printing mechanism 15 is shown as is necessary to properly set forth the invention.

The registering segment 43 (Fig. 1) is in mesh with a pinion 70 secured to the left hand end of a telescopic sleeve 71 which extends through the right hand side frame 44 of the machine into the printing mechanism, where it has secured to its right hand end a printing wheel 72 (Fig. 2). There is a printing wheel for each denominational group of 25 registering keys which print the detail transactions on a record strip and also upon the two receipts issuing strips which will herein-after be described.

The printing mechanism is operated by a 30 manually operated crank 73 (Fig. 2) which is rotated in a clockwise direction to drive a cam shaft 74 in a counter-clockwise direction. The operating crank 73 is freely mounted on a stud 75 supported in a printer 35 frame 76 and is secured to a sleeve which has mounted on its inner, or left hand, end a pinion 77, which meshes with a gear 78 securely mounted on the cam shaft 74. The shaft 74 and gear 78 are of such proportion 40 that it requires two revolutions of the crank 73 to cause one revolution of the cam shaft 74.

Formed in the side of the gear 78 is a cam race 79 which engages a roller 80 carried on 45 a stud mounted in an arm 81 pivoted on a pin 82 which is supported in the printer frame 76. The left hand, or forward, end of the arm 81 carries a stud 83 engaging an elongated opening 84 formed in an impression platen bearing member 85, which has a downwardly projecting arm 86 bifurcated to straddle the operating crank sleeve to guide the platen bearing member in its vertical movement.

55 The cam race 79 is formed so as to raise and lower the platen bearing member 85 during each operation of the machine to make the proper legible impressions upon the issuing receipt 87, as shown in Fig. 7.

60 The platen bearing member 85 (Fig. 2) supports four platens 92 which cooperate with the printing wheels 72, an electroplate 93, date and consecutive number printing wheels 94 and an electroplate 95 to print the 65 two receipts shown in Fig. 7.

The receipts are printed and severed from a strip 96 which is unwound from a supply roll (not shown) and passes under guide studs 97 and 98, between an inking ribbon 99 and the impression platens, and between two 70 feed rollers 100 and 101 past a severing plate 102.

The feed rollers are of standard form for this type of machine. The lower roller 100, which is the driving roller, is operated by 75 a pawl and ratchet mechanism, not shown here but fully described in the application previously referred to. The pawl is mounted on an arm secured to a shaft 103 (Fig. 3) which is oscillated by a pinion 104 pinned to the shaft and meshing with a segment arm 105 freely mounted on a stud 106 supported in the frame of the machine. The segment arm is oscillated during each operation of the machine by a pair of cams 107 and 108 secured to the shaft 74 and engaging rollers 109 and 110, respectively, which are carried on studs mounted in the segment arm.

The tension roller 101 is mounted on a 80 spring tensioned arm 115 pivoted at a point 116 and provided with a laterally projecting pin 117 engaging a manually operated lever 118 to enable the operator to disengage the tension roller from the feed roller when 85 starting a new supply of receipt paper.

The inking ribbon 99, being of the usual endless belt type, is given a slight movement during each operation of the machine by a 90 roller 119, the driving mechanism for which is not shown here but is fully illustrated and described in the application previously referred to. The ribbon is held taut by a tension roller 120.

To make it possible to issue two receipts 95 during one operation of the machine it is necessary to have a controlling mechanism which will compel two operations of the printing mechanism and four cycles of the operating crank 73 to one operation of an 100 item key 30.

Depression of an item key which raises the key coupler 32 (Fig. 1) and allows the arm 33 to swing forward under said key coupler and retain it in its raised position 115 and the key in its depressed position, rotates the shaft 50 through an angle of 180°. Pinned to the right hand end of the shaft 50 is a disk 119 (Fig. 3) having a cam race 120 engaging a roller 121 carried on an arm 122 115 freely mounted on a stud 123. As the disk 119 moves in a counter-clockwise direction it will cause the arm 122 to swing on its pivot to the extent of elevating its projection 124 above a roller 125 carried by a bell crank 125 lever 126. This bell crank lever is under the tension of a spring 127 which causes the lever to move clockwise when the projection 124 is raised above the roller 125. The clockwise movement of the lever 126 will 130

disengage its right hand end 128 from a square pin 129 mounted on a disk 130 fastened to the cam shaft 74.

Freely mounted on the stud 123 and fastened to the arm 122 by a stud 131 is a three-armed lever 132 which moves in unison with arm 122. Carried on a stud mounted in the left hand arm 133 of this lever is a roller 134 normally engaging the lower one of two notches 135 formed in a spring-pulled arm 136 freely mounted on a stud 137. As the lever 132 is moved clockwise by the cam 120, the roller 134 moves from the lower to the upper notch 135, where it retains the lever in its operated position until the lever is returned to its normal, or home, position after the two receipts have been printed.

A right hand arm 139 of the lever 132 normally engages a plate 140 pinned to the cam 107. When the arm 122 moves clockwise both arms 128 and 139 will disengage from their respective stop members 129 and 140 and permit the shaft 74 to be rotated by the operating crank 73 (Fig. 2).

The lever 126 (Fig. 3) is pinned to a rod 145 supported in the frame of the machine. An arm 146 (Fig. 1) also pinned to this rod carries a pin 147 which engages a bifurcated projection 148 on the arm 33 to rock the arm counter-clockwise under the key coupler at the time the key 30 is depressed.

The reason for having the two arms 128 and 139 (Fig. 3) engaging separate members to normally prevent rotation of the shaft 74 is that the arm 128 is provided to lock the shaft until the arm 33 (Fig. 1) is under the key coupler. The arm 139 locks the shaft 74 until the shaft 50 has received its initial movement. Were it not for the arm 128 it would be possible, by manipulation of the parts associated with the arm 33, to operate the printing mechanism without retaining a key 30 in depressed position.

The number of cycles of operation of the cam shaft 74 (Figs. 3 and 4) is controlled by a cam 149 secured to the shaft 74 cooperating with a rotatable plate 150 freely mounted on a stud 151 supported in the lever 132. The plate 150 has four arms, one of which will engage the cam 149 during the second cycle of operation of the cam shaft 74. The plate is retained in its various radial positions by a spring-tensioned pawl 152 engaging a ratchet wheel 153 which is secured to the plate.

The plate 150 is rotated in a counter-clockwise direction by a spring-tensioned pawl 154 pivoted at 155 to an arm 156 which is freely mounted on the stud 151. This arm carries a roller 157 engaging an elongated opening 158 formed in the segment arm 105. As the segment arm moves counter-clockwise, as previously described, the arm 156 will be moved in a like direction

and rotate the plate 150 a space equal to one division of the ratchet wheel 153.

Referring to Figs. 3 and 4 the parts are shown in their home positions. As the disk 119 is rotated 180° by the downward movement of an item key 30, the plate 150 will be placed in a cooperating position with the cam 149, but as the segment arm 105 is moved in a counter-clockwise direction before the cam 149 reaches a position to engage the plate 150, this plate will have been rotated one division of movement placing it in a relation to the cam 149 as shown in Fig. 5, in which position the cam will rotate without engaging the plate, thereby allowing the shaft 74 to continue rotating for a second cycle of operation. During the second cycle of operation the segment arm 105 will operate as during the first cycle and will again cause the arm 156 to rotate the plate 150 one division of movement which will place the plate in a relation to the cam 149 as shown in Fig. 6, in which position the cam will engage an arm of said plate and cause the lever 132 to move on its pivot in a counter-clockwise direction, moving the roller 121 in the radial slot of the disk 119 toward the shaft 50, and raising the arm 139 into position to engage the stop member 140 and stop the operation of the machine after the second cycle of operation.

As the roller 121 is moved toward the shaft 50 it enters the circular slot 120 of the disk, permitting the shaft 50 to complete its rotation and return the depressed item key 30 and its associate parts to their home position.

In the modified form shown in Figs. 8, 9 and 10, the mechanism is substantially the same as that shown in the first embodiment.

The shaft 50 is given a rotation of 180° by depressing an item key, which causes the cam 120 to move the arm 122 into the position shown in Fig. 9, where it is retained by a spring-tensioned arm 164 pivoted at 137 and having a shoulder 165 engaging a flat sided pin 166 fastened in an arm 167 of a three-armed lever 168 freely mounted on the stud 123 and secured to the arm 122 by a stud 131.

Pivoted on a stud 169 carried by the lever is a spring-tensioned bell crank arm 170 which is engaged by a cam 171 at each revolution of the cam shaft 74 to which said cam is secured.

During the first cycle of the shaft 74 the cam 171 will engage the arm 170 and cause it to swing on its pivot 169 in a counter-clockwise direction as the lever 168 upon which it is mounted is prevented from moving in a similar direction by the shoulder 165 engaging the flat sided pin 166. Near the end of the first cycle of the shaft 74 a cam 172 pinned to the shaft will engage a roller 173 carried on the right hand end of

a lever 174 and cause said lever to rock on its pivot 123 and swing the arm 164 clockwise on its pivot to disengage the shoulder 165 from the flat sided pin 166, as shown in Fig. 10. The left hand end of the lever 174 is formed on an angle where it engages a roller 175 carried on the lower end of the arm 164.

With the flat sided pin 166 disengaged from the shoulder 165 a spring 176 will move the lever 168 and arm 122 counter-clockwise until the projection 124 on the arm 122 engages the roller 125 carried on the lever 126, where it will be arrested until the cam 171 engages the bell crank arm 170 during its second cycle of operation, when the lever 168 and its associate parts will be returned to their home position by the cam 171, and the shaft 74 will be stopped after its second cycle as in the first embodiment. A spring 177 attached to the lever 126 is of greater strength than the spring 176 attached to the arm 167 which will prevent the lever 126 moving counter-clockwise until moved by the cam 171. With the arm 122 in its home position the shaft 50 will continue its rotation to return the item key and its associate parts to their home position as in the first embodiment.

30

Operation.

The amount to be printed on the two issuing receipts is set up on the type wheels by depressing the amount keys 30 corresponding to the amount.

After depressing the amount keys the operating crank 73 is given four turns in a clockwise direction, which gives two operations to the printing mechanism to print and issue two receipts, as shown in Fig. 7. Near the end of the printing operation the depressed amount keys are automatically returned to their home position.

While the form of mechanism herein shown and described is admirably adapted to fulfill the objects primarily stated, it is to be understood that it is not intended to confine the invention to the one form of embodiment herein disclosed, for it is susceptible of embodiment in various forms, all coming within the scope of the claims which follow.

What is claimed:

1. In a machine of the class described, the combination of a driving shaft having an initial movement and a final movement, a second driving shaft adapted to make a plurality of cycles during an operation of the machine, means for holding said second driving shaft to prevent an operation thereof, means operated by said first driving shaft during its initial movement for moving said holding means to permit operation of said second driving shaft, means on said second driving shaft for moving said hold-

ing means into position to stop said shaft, and means adapted to prevent said holding means from being moved into stopping position during certain cycles of said second driving shaft.

70

2. In a machine of the class described, the combination of a driving shaft having an initial movement and a final movement, a second driving shaft adapted to make two cycles during an operation of the machine, means for holding said second driving shaft in home position, a cam on said first driving shaft adapted to move said holding means during the initial movement of said shaft to permit said second driving shaft to operate, a latch member adapted to retain said holding means in its ineffective position, a lever adapted to operate said latch to release said holding means, a cam on said second driving shaft for operating said lever, and means for returning said holding means to its home position to stop said second driving shaft.

75

3. In a machine of the class described, the combination of a driving shaft having an initial movement and a final movement, a second driving shaft adapted to make two cycles during an operation of the machine, means for holding said second driving shaft in home position, a cam on said first driving shaft adapted to move said holding means during the initial movement of said shaft to permit said second driving shaft to operate, a latch member adapted to retain said holding means in its ineffective position, a lever adapted to operate said latch to release said holding means, a cam on said second driving shaft for operating said lever, and means for returning said holding means to its home position to stop said second driving shaft at the completion of its second cycle.

80

4. In a machine of the class described, the combination of a driving shaft adapted to make two cycles during an operation of the machine, means for holding said driving shaft in home position, means adapted to move said holding means to permit said driving shaft to operate, a latch member adapted to retain said holding means in its ineffective position, a lever adapted to operate said latch to release said holding means, a cam on said driving shaft for operating said lever, and means for returning said holding means to its home position to stop said second driving shaft.

85

5. In a machine of the class described, the combination of an operating shaft, a cycle controlling means, amount keys, and means operated by the keys for releasing the operating shaft and for establishing a cooperative relation between said cycle controlling means and shaft for releasing said keys

90

105

110

115

120

125

130

after a plurality of cycles of movement of said shaft.

6. In a machine of the class described, the combination of an operating shaft, a cam on said shaft, a cycle controlling means, amount keys, and means operated by the keys for releasing the operating shaft and for establishing a cooperative relation between said cycle controlling means and cam for releasing said keys after a plurality of cycles of movement of said cam.

7. In a machine of the class described, the

combination of an operating shaft, a cam thereon, a cycle-controlling means movable from home position into a position to be 15 operated upon by said cam without effect during the first cycle of operation, and means for moving said controlling means toward home position during the first cycle of operation into a position in which it is operated upon by said cam to stop the operating shaft.

In testimony whereof I affix my signature.

EDWARD J. VON PEIN.
